UNITED STATES PATENT OFFICE.

ALEXANDER J. STOESER, OF CHICAGO, ILLINOIS.

MACHINE FOR MAKING CONCRETE WALLS.

No. 839,667.

Specification of Letters Patent.

Patented Dec. 25, 1906.

Application filed August 8, 1904. Serial No. 219,839.

To all whom it may concern:

Be it known that I, ALEXANDER J. STOESER, a citizen of the United States, residing at Chicago, in the county of Cook and State 5 of Illinois, have invented certain new and useful Improvements in Machines for Molding Concrete Walls, of which the following is a full, clear, and exact specification.

My invention relates to devices for molding walls of plastic material commonly called "concrete," and it has more especial reference to that class of said machines in which a plurality of mold members are employed and so arranged as to produce separate mold- 10 cavities for respectively molding inner and outer sections of a hollow wall, and the mold members are relatively movable for the two-fold purpose of facilitating the removal of the mold from the wall and for making the walls 15 of various thickness.

The improvements relate more especially to the means for thus moving the members; and my invention has for its primary object to provide improved and efficient means for 20 that purpose which shall be at once simple and capable of rapid manipulation without jarring or defacing the newly-molded section and will be entirely without tendency to bind 25 on the parts which secure the members together.

With these ends in view my invention consists in certain features of novelty in the construction, combination, and arrangement of parts by which the said objects and certain 30 other objects hereinafter appearing are attained, all as fully described with reference to the accompanying drawings, and more particularly pointed out in the claims.

In the said drawings, Figure 1 is an end 35 elevation of my improved machine with the end board at one end omitted. Fig. 2 is a plan thereof, partly broken away and partly sectioned, showing the end boards at both ends in place. Fig. 3 is a front elevation of a 40 part of one end of the machine. Fig. 4 is an enlarged detail view of the eccentric and its connected parts in section on the line 4-4, Fig. 3. Fig. 5 is a transverse section thereof on the line 5-5, Fig. 4; and Fig. 6 is a detail 45 plan view of one of the end walls or boards.

1 2 3 4 are upright plates which constitute the sides of two mold-cavities 5 6, arranged at a distance apart, with an air-space 7 between them, and which plates may be provided 50 at top and bottom with flanges 8 9, serving to stiffen them longitudinally and to

afford better support for the machine on the surface upon which it rests. These mold members 1 2 3 4 are connected together across the top by transverse rods 10 11, the 60 rods 10 being arranged near the ends and the rod 11 at about the mid-length, and it might be stated that the number of the rods 11 employed are immaterial, since the purpose of the same is to stiffen the structure and prevent 65 the possibility of torsional strain upon the rods 10 and of the bending or sagging of the mold members between the rods 10. At least two of the mold members are movable laterally with relation to their companion 70 members, so that the machine may be readily lifted or disengaged from the newly-molded sections of the wall, which, as will be understood, are molded in the mold-cavities 5 6 in the usual way directly upon the wall. For 75 this purpose I have elected to make the outer member 1 of mold-cavity 5 and the inner member 3 of the mold-cavity 6 thus movable, the member 1 moving outwardly away from its cavity to increase the width thereof 80 and the member 3 moving toward the air-space 7, but also increasing the width of the mold-cavity 6, whereby both sections of the wall will be released, permitting the machine 85 to be lifted off. The other mold members 2 and 4 are rigidly but adjustably secured to the cross-rod 10 11, so that when desired the width of the mold-cavity 5 6 may be varied for producing walls of various thicknesses. In order that the mold members 90 may be thus supported, moved, and adjusted, the member 4 is provided with a number of collars 12 13, the former of which are secured to the rods 10 by means of set-screws 95 15 or other suitable devices and the latter to the rods 11 by set-screws 16 or other suitable means. The member 3 is provided with collars 17 18, the former of which is slidably mounted upon the rods 10, one at each end of the machine, as shown in Fig. 2, and the 100 latter of which is slidably mounted on the rod 11, while the mold member 2 is supported upon the rods 10 or 11 by means of collars 19 20, respectively, and held thereon in any suitable way, as by set-screws 21, in a manner similar to that described with reference to the member 4. The member 1, although bodily adjustable with relation to its companion member 2 and also movable outwardly away from the same to release the 105 machine from the wall, is constructed to turn on a hinge or pivot, which is constituted by

the shaft 22 or other suitable means arranged above the level of the upper edges of the mold-cavities and extending longitudinally of the plate or member 1. This member is 5 also capable of sliding on the rods 10 11, however, like the other members when it is desired to increase the width of the mold-cavity 5 for molding a wall of different thickness, and to that end such mold member is 10 provided with sliding collars 23 24, mounted upon the rods 10 11, respectively, one of the collars 23 being arranged at each end like the collars 12, 17, and 19, and these collars 23 24 are provided with suitable fastening devices, 15 such as set-screws 25 26. The collars 23 24 are supported from the shaft or rod 22, and the mold member 1 is provided with additional collars 27 28, which are also journaled loosely upon the shaft 22, so that the member 20 1 may swing freely about the center constituted by said shaft. All of the collars with the exception of the collars 23 24 are rigidly connected to their respective mold members 1 2 3 4 by any suitable means, such 25 as arms 29, all practically the same in construction and extending downwardly on and secured to the outer faces of their respective mold members, as better shown in Figs. 1 and 3, and, if desired, the flanges 8 on the 30 mold members may be let into the arms 29, as shown in Fig. 1, for the purpose of stiffening said flanges.

In order that the rotary or pivotal movement of the mold member 1 may be imparted 35 to the movable member of the other mold-cavity—the member 3, for example—the latter is operatively connected to the member 1, and such connection is capable of adjustment, so that when the operative position of 40 the member 3 is altered the operation of said connection will not be interfered with. This operative connection preferably consists of a plurality of eccentrics 30, arranged one at each end of and preferably secured to the 45 shaft 22 and near the ends of the member 1, so that the rotation of one eccentric will be imparted to another and their movement will be uniform, and eccentric-straps 31, journaled on the eccentrics and connected to the 50 member 3 by suitable means, as rods 32 and pins 33, adapted to be inserted through any one of the series of holes 34 in the rods 32, the pins 33 having suitable attachment to the member 3, preferably through the intermediary of a pair of lugs 35 on the upper side of each of the collars 17, and through which lugs the pins 33 pass, while the rods 32 pass between them and are arranged directly over the bars 10 and collars 19, so as to avoid obstructing the mold-cavities 5 6. The eccentrics 30 are located to one side of the collars 23, and their straps have offset arms 36 conjoined with the rods 32. It will thus be seen 60 that when the lower edge of the member 31 65 is thrown outwardly about the center 22 the eccentrics 30 will simultaneously impart a pull to the rods 32, and thereby draw the collars 17 along the bars 10 with a powerful but uniform and steady movement, the mold-cavity 6 being relieved by this movement of the member 3 and the mold-cavity 5 by the outer swinging movement of the member 1, which movement, taking place as it does about the elevated center 22, causes the upper as well as the lower edge of member 1 to 70 recede from the mold-cavity. In order that the member 1 may be locked in position, one or more braces 37, preferably one at each end, are provided. These are pivoted in lugs 38 near the lower edge of member 1 and pass 75 through slotted arms or keepers 39, projecting horizontally from the collars 23 and having set-screws 40, whereby the braces 37 may be locked in position. The member 4 is similarly braced at its lower edge by immovable braces 42, secured to the member 4 near its lower edge and to projecting ends of the bars 10 11 by set-screws 43 or other suitable means. The ends of the mold-cavities 5 6 are closed by end boards which are both removable and adjustable to allow for the before-described movements and adjustments 80 of the side members of said cavities. These end boards are similar in construction, and the description of one with reference to Figs. 1, 3, and 6 will suffice for all. It consists of two plates 44 45 overlapped and adjustably secured together by set-screws 46 passing through one and into slots 47 in the other, and the edges of the plates 44 45 have upright flanges 48 49, provided with notches 50, which engage over buttons 51 on the side of the mold members, and thereby not only lock the end boards in position, but also constitute braces for reinforcing when the set-screws 46 are tight for holding the inner members 2 3 from spreading.

Having thus described my invention, what I claim as new therein, and desire to secure by Letters Patent, is—

1. In a machine for molding concrete walls the combination of a plurality of members arranged to produce separate mold-cavities, one of said members being pivotally movable and means for sliding another of said members toward and from its mold-cavity, comprising an eccentric movement operatively connected with said pivotal member.
2. In a machine for molding concrete walls the combination of a plurality of members arranged to produce separate mold-cavities, one of said members being pivotally movable, and means for moving another of said members toward and from its mold-cavity, comprising an eccentric movement operatively connected with said pivotal member.
3. In a machine for molding concrete walls the combination of a plurality of members arranged to produce separate mold-cavities, one of said members being pivotally mov-

able, and means for moving another of said members toward and from its mold-cavity, comprising connected eccentrics and a connection between each of said eccentrics and one end of the pivotal member and the other member to be moved.

4. In a machine for molding concrete walls the combination of a plurality of members arranged to produce separate mold-cavities, one of said members being pivotally movable and means for moving another of said members toward and from its mold-cavity comprising eccentrics, eccentric-straps on said eccentrics having offsets, means for connecting the eccentrics with the pivotal member, and rods secured to said offsets and connected with the other of said members to be moved, bars supported across the said members, and collars connecting said bars and members, said collars being arranged directly under said rods and said eccentrics being arranged to one side of said bars.

5. In a machine for molding concrete walls the combination of a plurality of members arranged to produce separate mold-cavities, one of said members being pivotally movable and means for moving another of said members toward and from its mold-cavity comprising eccentrics and an operative connection between the latter one of said members and said eccentrics, said eccentrics being operatively connected with said pivotal member, and means for adjusting said operative connection between said member to be moved thereby and the eccentrics, whereby the thickness of the wall may be varied at will.

6. In a machine for molding concrete walls the combination of a plurality of members arranged to produce separate mold-cavities, one of said members being pivotally movable, and means for moving another of said members toward and from its mold-cavity comprising a pin connected therewith, a rod having a series of holes through any one of which said pin may be passed, and means operatively connecting said rod with said pivotal member for reciprocating the rod.

7. In a machine for molding concrete walls the combination of a plurality of members arranged to produce separate mold-cavities, one of said members being pivotally movable, means for moving another of said members toward and from its mold-cavity operatively connected with said pivotal member, and means for holding said pivotal member against pivotal movement.

8. In a machine for molding concrete walls the combination of a plurality of members arranged to produce separate mold-cavities, one of said members being pivotally movable, means for moving another of said members relatively to its mold-cavity, operatively connected with said pivotal member, a brace connected with said pivotal member

for holding it against pivotal movement, a keeper in which said brace slides and means for locking said brace and keeper together.

9. In a machine for molding concrete walls the combination of a plurality of members arranged to produce separate mold-cavities, one of said members being pivotally movable, means for moving another of said members relatively to its mold-cavity operatively connected with said pivotal member, slotted arms rigidly supported independently of said pivotal member and braces pivoted to said pivotal member and working in said slotted arms.

10. In a machine for molding concrete walls the combination of a plurality of members arranged to produce separate mold-cavities, one of said members being pivotally movable, a shaft supported lengthwise of said pivotal member and constituting the pivot thereof, a plurality of eccentrics on said shaft rotatable in unison with said pivotal member and means operatively connecting said eccentrics with another one of said members for moving the latter relatively to its mold-cavity.

11. In a machine for molding concrete walls the combination of a plurality of members arranged to produce separate mold-cavities, means for supporting said members adjustably with relation to each other whereby the size of the mold-cavities may be varied, and detachable end walls for said mold-cavities comprising overlapped plates slidably connected together and means for connecting the edges of said plates to said members.

12. In a machine for molding concrete walls the combination of a plurality of members arranged to produce separate mold-cavities, means for supporting said members adjustably with relation to each other, and end walls for said mold-cavities comprising overlapped plates slidably connected together and having notched flanges turned inwardly and overlapped with the ends of said members and buttons on the ends of said members adapted to engage in the notches of said flanges for holding the end walls in place.

13. A molding-machine consisting of two sets of sides yoked together with one member of one set between the members of the other set, said members forming mold-chambers with an intervening space, and means for simultaneously adjusting one member of each of said mold-chambers and closing the ends thereof.

14. In a machine for molding concrete walls, the combination of a plurality of mold-cavities, each of said cavities comprising separable sections, one section of one cavity being pivotally movable, and means operatively connecting the pivotal section with one of the sections of another cavity, whereby said latter section will be given a sliding movement with relation to its co-operating

section when the pivotal section is moved about its pivot.

15. In a machine for molding concrete walls, the combination of a plurality of mold-cavities, each of said cavities comprising separable sections, one section of one cavity being pivotally movable, means operatively connecting the pivotal section with one of the sections of another cavity, whereby said

latter section will be given a sliding movement with relation to its co-operating section when the pivoted section is moved about its pivot, and adjustable end members for said cavities.
